Application June 14, 1944, Serial No. 540,201

16 Claims. (Cl. 242—58)

1

This invention relates to the continuous supply of webs to web consuming apparatus such as printing presses, paper perforating and winding machines, envelope and bag making machines and the like. The invention particularly concerns an improved apparatus for replacing the roll supplying the web to such apparatus without interrupting or retarding the speed of web travel and without any undesirable variation in the tension on the web.

The paper or other flexible web fed to a printing press or other web consuming apparatus runs from rolls which must be replaced periodically as they are consumed. High speed web roll replacement has heretofore been accomplished by mechanism in which a new roll bearing a layer of adhesive at the leading end of its web is brought to a position adjacent the running web and is accelerated to the speed of the running web. Thereafter, when the roll supplying the running web has been consumed to a point near its end, the leading end of the web on the new roll is spliced to the running web and the web from the expiring roll approaching the new roll surface is severed. Prior to the splicing operation, the desired tension of the running web is maintained by suitable members usually in the form of yieldable belts, straps or the like which engage the surface of the running roll. The web tension may be varied by moving the running roll into or out of the belts or straps to increase or decrease the extent to which these tension members wrap around the roll surface. After a splice is made and the web from the expiring roll is severed, the tension derived from contact between the expiring roll and the tension members is lost and the operator must thereafter move the new roll to a running position in which the wrap of the tension members on its surface is sufficient to replace the tension lost when the old web was cut. The inevitable delays and irregularities that result from manual control of this tension increasing operation give rise to undesirable variations in web tension which adversely affect the operation of the web consuming apparatus.

The objects of the present invention include the provision of an improved apparatus for so co-ordinating the web splicing, web severing and tension applying operations that web roll replacement is made without any undesirable decrease or other variation in the tension on the web fed to the press or other consuming apparatus. More specifically, the invention contemplates a method and apparatus in which the old web is severed immediately after the splice is made, and simultaneously with or immediately after the

5 severing of the old web, the new web roll is moved to a running position in which adequate tension is applied to its surface and so imposed on the web running therefrom. The objects of the invention further embrace a method and apparatus in which the application of or increase in tension applied through the new roll when the splice is made is governed by movement of the spliced end of the new roll web away from the roll surface with the running web. Other specific objects, 10 advantages and characteristic features of the invention will be apparent from the appended description of certain typical embodiments thereof.

In general, the above noted and other objects 15 of the invention are carried out by the provision of a control actuator on the web of the new roll adjacent its leading end, together with means responsive to the movement of this actuator away from the new roll surface along the running web for both severing the web from the old roll and 20 moving the new roll relative to the tension applying members. The invention is applicable to web replacement operations in which ordinary tacky adhesive is used to make the splice, and also to 25 operations of the type described and claimed in my Patent No. 2,320,656 in which self-sticking adhesive is used for this purpose.

In describing the invention in detail, reference 30 will be made to the accompanying drawings in which certain embodiments thereof have been illustrated. In the drawings:

Fig. 1 is a simplified and diagrammatic side elevation of apparatus embodying the invention;

Fig. 2 is an end elevation of a portion of the apparatus shown in Fig. 1;

Fig. 3 is a side elevation similar to Fig. 1 showing the reel mechanism on an enlarged scale;

Fig. 4 is a sectional view taken along the line 4—4 of Fig. 1 and viewed in the direction of the arrows;

Figs. 5, 6 and 7 are respectively side elevations similar to Fig. 1 showing the apparatus in three successive operating positions;

Fig. 8 is a perspective view of a new roll prepared for splicing in the apparatus of Fig. 1;

Fig. 9 is a perspective view on an enlarged scale of a paster tab which may be employed in conjunction with the invention;

Fig. 10 is a simplified and diagrammatic side elevation of apparatus embodying the invention and designed for use in connection with web splicing operations in which self-sticking adhesive is employed;

Figs. 11 and 12 are respectively elevations similar to Fig. 10 showing a portion of the apparatus in successive operating positions;

Fig. 13 is a perspective view of a new roll prepared for pasting in the apparatus illustrated in Fig. 10; and

Fig. 14 is a perspective view on an enlarged scale of a paster tab of the type shown on the roll of Fig. 13.

Referring to the drawings, in Figs. 1, 2 and 3, there is shown a three-roll reel comprising a spider 26 having three radially extending angularly spaced arms 15, 16 and 17 respectively carrying spindles 18, 19 and 20 on which rolls 21, 22 and 23 are rotatably supported. The web of the rolls illustrated may comprise paper for use in a printing press or any other thin flexible material. A reel shaft 24, journaled in the stand 25 is formed integrally with or secured to the spider 26. It will be understood that a like spider, shaft and stand is provided at the opposite ends of the rolls. As shown in Fig. 1, the reel is in such a position as to place the roll 21 in what will be termed the 20 splicing position.

Adjacent the reel is a tension mechanism of known construction in the form of one or more running belts 27 disposed parallel to the cylindrical surfaces of the rolls on the reel. The belts 25 27 are generally spaced axially of the rolls and travel over the idler pulleys 28, 29, 30, 31 and 32, the weighted compensator pulley 33 and the drive pulley 34. The pulley 34 is driven at a speed such that its peripheral velocity is close to but slightly 30 below that of the web 36 running to the press or other web consuming apparatus. This drive may be effected through suitable means such as a shaft 35 connected to the web consuming apparatus.

Means are provided for accelerating a roll in the splicing position to web speed before the splice is made. In the illustrated embodiment, a traction belt 37 of known construction is employed for this purpose. The belt is carried by three triangularly disposed rollers 38, 39 and 40 supported on a pivoted arm 41 biased to press the belt 37 against the surface of the roll 31 by suitable means such as a spring 42. The rollers 38, 39 and 40 are driven at substantially web speed by suitable means such as the belts or chains 43, 44, 45 and 46.

A brush and knife arm 47 is pivotally connected at its upper end to a fixed support 48. As best shown in Fig. 4, the arm 47 is keyed to a shaft 49 journaled in the support 48 and a worm wheel 50 is rotatably journaled on the shaft 49 adjacent the outside face of the arm 47. Friction discs 51 are disposed on either face of the worm wheel 50 and a hand wheel 52, threaded on the shaft 49, serves to clamp the worm wheel 50 against the face of the arm 47 between the discs 51. Loosening the hand wheel 52 releases the worm wheel 50 and so permits the arm 47 to swing by gravity to the vertical position shown in Fig. 1. A worm 53 meshing with the worm wheel 50 and driven by a motor 54 turns the wheel 50 in a counterclockwise direction as viewed in Fig. 1 to lift the arm 47 away from the reel when the worm wheel 50 is clamped to the arm 47.

The arm 47 carries a pasting brush 55 on a bell crank lever 56 pivoted at 57. A slidably supported rod 58 connected to the operating arm of the bell crank lever 56 is biased by a spring 59 to swing the brush 55 outward when released by the energization of a brush solenoid 60 having a latch armature 61. A web cutting knife 62 pivotally connected to the arm 47 at 63 is similarly biased to move to its extended position by a spring 64.

on a sliding rod 65 when the latch armature 66 is retracted by energization of the knife solenoid 67. The reel is rotated by suitable means such as a motor 68 mounted on the stand 25 and driving a worm 69 which meshes with a worm wheel 70 fixed to the reel shaft 24 (Figs. 1, 2 and 3). Means are provided for starting and stopping the reel and arm driving motors 68 and 54 in accordance with the web splicing operation and the movement of the reel. In the disclosed embodiment, a solenoid 71 is mounted on the reel stand 25 and has an armature 72 connected to a pair of movable contacts 73 and 74 which respectively connect the fixed contacts 75-76 and 77-78 when the solenoid is energized. The upper end of the armature 72 comprises a latch 79 which engages a spring biased latch 80 pivotally connected at 81 to the stand 25 when the solenoid is energized to lift its armature (Fig. 6). A stud 82 extends outwardly from the face of the latch 80 and is disposed to be engaged by one of the three latch trip pins 83, 84 and 85 carried at equally spaced points on a disc 86 rotatably mounted on the reel shaft 24. The disc 86 is connected to turn with the reel shaft through adjusting means including a rod 88 threadedly engaging a stud 90 on the disc 86 and journaled in but held against axial movement through a stud 91 on a radial extension 92 of the disc 86. Rotation of the rod 88 by means of the hand wheel 93 moves the disc 86 relative to the shaft 24 and so provides a fine adjustment of the position of the latch trip pins 83, 84 and 85 with respect to the positions of the reel arms 15, 16 and 17. With the arrangement described, rotation of the reel to a position in which one of the pins 83, 84 or 85 strikes the stud 81 on the latch 80 causes disengagement of this latch from the solenoid armature latch 79 and so permits the contacts 73 and 74 to drop and disengage the fixed contacts 75-76 and 77-78.

The splicing and reel turning operations are governed by control actuators preferably carried at or adjacent the leading end of the web on each new roll. One such roll 21 prepared for splicing has been illustrated in Fig. 8. The leading end of the web on this roll may be formed into points 94 in accordance with known practice, and these points are releasably held to the underlying layer of web forming the roll surface by means such as paster tabs 95 and 96. These tabs generally comprise a web end engaging part 97 secured to the web end by a strong adhesive, and a roll surface engaging part 98 similarly secured to the adjacent roll surface together with a weakened portion which may comprise a transverse roll of perforations 99 connecting the parts 97 and 98 at or adjacent the edge of the web. Layers 131 of tacky splicing adhesive are spread on axially spaced areas of the web end and the tension belts 27 contact the roll surface between and outside of these adhesive coated areas in a manner well known in the art.

One of the paster tabs, here illustrated as the tab 95, is constructed to carry control actuators. In the illustrated embodiment, the web end engaging part of this tab comprises an outer portion 100 and an under portion 101, and these portions are respectively secured to the outer and under surfaces of the web end. A control actuator 102 comprising a conductive layer of metal foil, metallic paint or the like, is disposed on the outer surface of the outer tab portion 100, and a similar conductive control actuator 103 is disposed on the under surface of the under tab

portion 101 (Fig. 9). It should be understood that the conductive control actuators 102 and 103 may be disposed directly on the outer and under surfaces of the web end rather than on tab portions secured thereto.

A pair of contact fingers 104 is disposed adjacent and in contact with the surface of the roll 21 in the splicing position. These fingers may be carried by but insulated from a shaft 105 of the roll accelerating mechanism as shown in Fig. 2. The fingers 104 are disposed in the path of the outer control actuator 102 so as to be electrically connected by this actuator as the roll 21 rotates. A similar pair of contact fingers 106 is mounted adjacent the web 36 where it travels away from the surface of the roll 21 in the splicing position. The fingers 106 are disposed to be electrically connected by the control actuator 103 on the under surface of the new web end just after the splice is made. A plate 107 may be provided to support the web 36 where it is contacted by the fingers 106.

The contact fingers 104 are connected in series with an energizing circuit for a relay 108, which circuit includes a source of energy represented by a battery 109 and a manually operable switch 110. The contact fingers 106 are connected in series with an energizing circuit for a relay 111, which circuit includes a source of energy represented by the battery 112. The relay 108 controls the brush solenoid 60 and the relay 111 controls the knife solenoid 67 and the reel control solenoid 71. Thus energization of the relay 108 closes its contacts 113, completing an energizing circuit from the source of energy represented by the terminals 114 through the wire 115, the solenoid 160, the wire 116, the contacts 113 and the wires 117 and 118. Energization of the relay 111 closes its sets of contacts 119 and 120. Closure of the contacts 119 energizes the knife solenoid 67 through a circuit including the wires 121, 122, 123 and 124. Closure of the contacts 120 energizes the solenoid 71 through a circuit including the wires 121, 125, 126 and 124. Energization of the solenoid 71 closes its contacts 73 and 74. Closure of the contacts 73 energizes the reel drive motor 68 from a source of energy represented by the terminals 127 through a circuit clearly shown in Fig. 1 of the drawings. Closure of the contact 74 energizes the arm driving motor 54 through a circuit including the wires 128 and 129. Closure of a manually operable switch 130 connected between one terminal of the reel motor 68 and one of the terminals 127 energizes the motor 68 independently of the solenoid operated contact 73.

The operation of the above described embodiment of the invention will now be described. When a web roll 22 from which the web 36 is running to the web consuming apparatus approaches depletion, the operator turns the reel to bring a new roll 21, prepared for splicing as above described, to the splicing position shown in Fig. 1. This is accomplished by closing the switch 130 and holding it closed until the roll 21 reaches the desired position. The operator also sets the brush 54 and the knife 62 to the positions shown in Fig. 1 and loosens the hand wheel 52 to permit the arm 47 to move to its vertical position, after which the hand wheel 52 is again tightened to clamp the arm to the worm wheel 50. The belt 37 is lowered into contact with the new roll 21 which is thereby accelerated until its peripheral velocity equals or substantially equals the running web speed, the direction

of rotation of the roll being indicated by an arrow. The operator then watches the expiring roll 22 and when it runs off to a point close to its end, he closes the switch 110. As soon as the roll 21 thereafter turns to the point where the control actuator 102 connects the contact fingers 104, the relay 108 is energized, closing its contacts 113 and so energizing the brush solenoid 60 to release the brush 55. The brush 55 snaps outward, pressing the running web 36 into contact with the surface of the new roll 21 (Fig. 5). When the roll 21 turns to the position in which its leading end contacts the running web 36, the tacky adhesive layers 131 stick the new web end to the running web to make the splice, the paster tabs 95 and 96 are severed along their weakened portions and the new web end moves away from the roll surface and travels with the running web. Immediately thereafter, the control actuator 103 on the under surface of the new web end electrically connects the contact fingers 106 whereby the relay 111 is energized and closes its contacts 119 and 120. This energizes the knife solenoid 67, releasing the knife 62 and so cutting the old web between the expiring roll 22 and the new roll 21. Energization of the relay 111 also energizes the reel solenoid 71, causing its armature 72 to latch in the closed position as shown in Fig. 6. Closure of the contacts 73 and 74 of the solenoid 71 energizes both the reel drive motor 68 and the arm drive motor 54. The reel is accordingly rotated in a clockwise direction as shown, advancing the newly spliced roll into the tension belts 27 to a running position in which the belts wrap around a considerable arc of the periphery of the roll 21, as shown in Fig. 7. As the reel is thus turned, the arm 47 is moved out of its path. When the reel reaches the running position, the pin 84 disengages the latch 80 and so permits the armature 72 of the solenoid 71 to drop, opening the contacts 73 and 74 and so de-energizing the reel and arm motors 68 and 54 (Fig. 7). The reel thus stops with the newly spliced roll 21 in the desired running position, which position may be adjusted as desired by manipulation of the hand wheel 93 as above described. When the apparatus has reached the running position, the operator relatches the brush arm 56 and the knife 62 and the new roll 21 runs until it nears depletion, whereupon the reel is advanced by manual operation of the switch 130 to place the next new roll 23 in the splicing position, and the above described operations are repeated.

In the above described embodiment, tacky adhesive is employed to make the splice. My invention is also applicable to splicing operations of the type described in my Patent No. 2,320,656 in which self-sticking adhesive is employed to splice the new web to the running web. Such an application has been illustrated in Figs. 10 to 14.

Referring to Fig. 10, the parts of the apparatus there illustrated which are identical with corresponding parts of the apparatus previously described are designated by like reference characters bearing distinctive exponents. This apparatus differs from that previously described primarily in that no new roll accelerating belts are employed, and the splicing brush and its operating contact fingers, circuits and control actuator are omitted. The knife relay 111' is energized by electrical connection of the contact fingers 106' engaging the under surface of the running web 36'. These fingers are connected by a control actuator 103' carried on the under surface 75 of the leading end of the web on the new roll

21'. The knife solenoid 67' acts directly when energized to extend the knife 62' to a position to sever the web.

The new roll 21' is prepared for pasting by separably securing its leading end to the roll surface, providing a control actuator 103' on the under surface of the leading web end and providing a layer of dried self-sticking adhesive 135 on the outer surface of the web at and adjacent its leading end. The adhesive comprising the layer 135 is of the type described in detail in my aforesaid Patent No. 2,320,656. This self-sticking adhesive may comprise a rubber cement and has the property of adhering to a paper or other web surface when applied thereto in liquid form and dried thereon. The applied and dried adhesive layer does not stick to an uncoated web surface but coheres tenaciously with an applied and dried layer of self-sticking adhesive carried into contact therewith by another web.

In the disclosed embodiment, the leading end of the web on the roll 21' is separably secured to the roll surface by paster tabs 136 and 137, one of which, in the illustrated case the tab 136, carries the control actuator 103' on the under surface of its under part 101'. The core end of the web on the roll 21' carries on its under surface a layer of applied and dried self-sticking adhesive extending longitudinally of the web for a distance at least as long as the circumference of the largest web roll to be spliced, and this applied and dried core end layer is illustrated at 138 in Figs. 10 and 11, this being the core end adhesive layer of the expiring roll 22'.

The operation of the modification illustrated in Figs. 10 to 14 will now be described. When the running roll 22' has been depleted to a point where replacement will soon be required, the operator turns the reel clockwise to place the new roll 21', prepared as described, in the splicing position which is illustrated in Fig. 10. The reel is so turned by closure of the manual switch 130'. The operator also drops the arm 47' to the vertical position shown in Fig. 10 by loosening the hand wheel 52' and then re-tightening this wheel. In the splicing position, the new roll 21' contacts the running web 36' backed by the belts 27', and the new roll 21' is accelerated to or substantially to web speed by this contact. During rotation of the roll 21' in contact with the web 27', the self-sticking adhesive layer 135 on the leading end of the new roll web repeatedly contacts the running web, but because of the above explained properties of the self-sticking adhesive, the running web is not stuck to the new roll web. When the old roll 21' runs out substantially to its end, the self-sticking adhesive layer 138 adjacent the core end thereof moves into contact with the cylindrical surface of the new roll 21' and contacts the self-sticking adhesive layer 135. The layers 135 and 138 stick tightly together upon contact, thus splicing the new web to the running web, and the new web is pulled away from the surface of the roll 21', breaking the tabs 136 and 137 and traveling along the running web 36'. Immediately thereafter, the control actuator 103' on the under surface of the new web end electrically connects the contact fingers 106', causing energization of the relay 111'. Closure of the relay contacts 119' energizes the solenoid 67', extending the knife 62' to sever the old web running from the roll 22' to the roll 21', as shown in Fig. 11. Closure of the contacts 120' energizes the solenoid 71', closing its contacts 73' and 74'. The armature 72' of the solenoid 71' is latched up by inter-engage-

ment of the latches 79' and 80'. Closure of the contacts 73' and 74' respectively energizes the reel drive motor 68' and the arm drive motor 54'. The reel is accordingly rotated clockwise, advancing the new roll 21' into the tension belts 27', and moving the expired roll 22' to a position where it can be removed and replaced by a new roll. The arm 47' is moved back out of the path of the reel as the reel turns. The pin 84' moves the latch 80' out of engagement with the latch 79', opening the contacts 73' and 74' and the reel and arm stops in the position shown in Fig. 12 where suitable running tension is applied to the roll 21' and thus to the web running therefrom.

15 I claim:

1. In apparatus for splicing the leading end of the web on a new roll to a web running past the surface of the new roll from an expiring roll after the new roll is accelerated to running web speed, 20 in combination with means for applying a variable tension to the surface of said rolls, a control actuator on the new roll web adjacent its leading end and means responsive to movement of said control actuator away from the surface of the new roll to increase the tension applied to the surface of the new roll.

2. In apparatus for splicing the leading end of the web on a new roll to a web running past the surface of the new roll from an expiring roll after the new roll is accelerated to running web speed, 30 in combination with a rotatable reel having spaced arms respectively carrying an expiring roll and a new roll, and tension means adjacent said reel for contacting the surface of the rolls on said reel to apply tension to the web running therefrom, a control actuator on the new roll web adjacent its leading end, and means responsive to movement of said control actuator away from the surface of said new roll for turning said reel to move said new roll into said tension means.

3. In apparatus for splicing the leading end of the web on a new roll to a web running past the surface of the new roll from an expiring roll after the new roll is accelerated to running web speed, 45 in combination with a rotatable reel having angularly spaced arms respectively carrying an expiring roll and a new roll and flexible tension means adjacent said reel for contacting variable portions of the surfaces of said rolls as said reel is rotated, a control actuator on the new roll web adjacent its leading end, and means responsive to the movement of said control actuator away from the surface of said new roll for turning said reel to increase the portion of the surface of the new roll contacted by said tension means.

4. In apparatus for splicing the leading end of the web on a new roll to a web running past the surface of the new roll from an expiring roll after the new roll is accelerated to running web speed, 60 in combination with a rotatable reel having angularly spaced arms respectively carrying an expiring roll and a new roll and flexible tension means adjacent said reel for contacting variable portions of the surfaces of said rolls as said reel is rotated, a control actuator on the new roll web adjacent its leading end, and means responsive to the movement of said control actuator away from the surface of said new roll for turning said reel to increase the portion of the surface of the new roll contacted by said tension means.

5. In apparatus for splicing the leading end of the web on a new roll to a web running past the surface of the new roll from an expiring roll after

the new roll is accelerated to running web speed, in combination with a rotatable reel having angularly spaced arms respectively carrying an expiring roll and a new roll and flexible tension means adjacent said reel for contacting variable portions of the surfaces of said rolls as said reel is rotated, a control actuator on the new roll web adjacent its leading end, means responsive to the movement of said control actuator away from the surface of said new roll for turning said reel in a direction to increase the portion of the surface of the new roll contacted by said tension means and means responsive to the turning movement of said reel for discontinuing such turning thereof.

6. In apparatus for splicing the leading end of the web on a new roll to a web running past the surface of the new roll from an expiring roll after the new roll is accelerated to running web speed, in combination with a rotatable reel having angularly spaced arms respectively carrying an expiring roll and a new roll and flexible tension means adjacent said reel for contacting variable portions of the surfaces of said rolls as said reel is rotated, a control actuator on the new roll web adjacent its leading end, and means responsive to the movement of said control actuator away from the surface of said new roll for turning said reel in a direction to increase the portion of the surface of the new roll contacted by said tension means, and means responsive to the turning movement of the reel for discontinuing such turning movement of the reel when the reel has turned to a predetermined position.

7. In apparatus for splicing the leading end of the web on a new roll to a web running past the surface of the new roll from an expiring roll after the new roll is accelerated to running web speed, in combination with a rotatable reel having spaced arms respectively carrying an expiring roll and a new roll, and flexible tension means adjacent said reel for contacting varying portions of the surfaces of the rolls on said reel as the reel is turned to different positions, a control actuator on the new roll web adjacent its leading end, means for splicing the leading end of the new roll web to the web running from the expiring roll, means responsive to movement of said control actuator away from the surface of said new roll after the splice is made for initiating rotation of said reel to advance the new roll into said tension means, and means including a part connected to said reel for discontinuing rotation of said reel when the new roll has been advanced to a predetermined extent.

8. In apparatus for splicing the leading end of the web on a new roll to a web running past the surface of the new roll from an expiring roll after the new roll is accelerated to running web speed, in combination with a rotatable reel having spaced arms respectively carrying an expiring roll and a new roll, and flexible tension means adjacent said reel for contacting varying portions of the surfaces of the rolls on said reel as the reel is turned to different positions, a control actuator on the new roll web adjacent its leading end, means for splicing the leading end of the new roll web to the web running from the expiring roll, means responsive to movement of said control actuator away from the surface of said new roll after the splice is made for initiating rotation of said reel to advance the new roll into said tension means, means including a part connected to said reel for discontinuing rotation of said reel when the new roll has been advanced to a predetermined extent and means for adjustably

varying the position of said part relative to the position of said reel whereby the extent to which the new roll is advanced may be varied.

9. In apparatus for splicing the leading end of the web on a new roll to a web running past the surface of the new roll from an expiring roll after the new roll is accelerated to running web speed, in combination with a rotatable reel having spaced arms respectively carrying an expiring roll and a new roll, and flexible tension means adjacent said reel for contacting varying portions of the surfaces of the rolls on said reel as the reel is turned to different positions, a control actuator on the new roll web adjacent its leading end, means for splicing the leading end of the new roll web to the web running from the expiring roll, means for severing the web running from the expiring roll, and means responsive to movement of said control actuator away from the surface of the new roll after the splice is made for actuating said web severing means and turning said reel to advance said new roll into said tension means.

10. In apparatus for splicing the leading end of the web on a new roll to a web running past the surface of the new roll from an expiring roll after the new roll is accelerated to running web speed, in combination with a rotatable reel having spaced arms respectively carrying an expiring roll and a new roll, and flexible tension means adjacent said reel for contacting varying portions of the surfaces of the rolls on said reel as the reel is turned to different positions, a control actuator on the new roll web adjacent its leading end, means for splicing the leading end of the new roll web to the web running from the expiring roll, means for severing the web running from the expiring roll, means responsive to movement of said control actuator away from the surface of the new roll after the splice is made for actuating said severing means and initiating rotation of said reel to advance the new roll into said tension means, and means responsive to the rotation of said reel for discontinuing rotation thereof when the new roll has been so advanced to a predetermined extent.

11. In apparatus for splicing the leading end of the web on a new roll to a web running past the surface of the new roll from an expiring roll after the new roll is accelerated to running web speed, in combination with a rotatable reel having spaced arms respectively carrying an expiring roll and a new roll, and flexible tension means adjacent said reel for contacting varying portions of the surfaces of the rolls on said reel as the reel is turned to different positions, a control actuator on the new roll web adjacent its leading end, means for splicing the leading end of the new roll web to the web running from the expiring roll, means for severing the web running from the expiring roll, means responsive to movement of said control actuator away from the surface of the new roll after the splice is made for actuating said severing means and initiating rotation of said reel to advance the new roll into said tension means, means including a part connected to said reel for discontinuing rotation of said reel when the new roll has been advanced to a predetermined position, and means for adjustably varying the position of said part relative to the position of said reel whereby the position to which the new roll is advanced may be varied.

12. In apparatus for splicing the leading end of the web on a new roll to a web running past

the surface of the new roll from an expiring roll after the new roll is accelerated to running web speed, in combination with means for applying a variable tension to the surfaces of said rolls, a control actuator on the under surface of the new roll web adjacent its leading end, means for splicing the outer surface of the leading end of the new roll web to the web running from an expiring roll, and means responsive to movement of said control actuator away from the surface of the new roll after the splice is made for increasing the tension applied to the surface of the new roll.

13. In apparatus for splicing the leading end of the web on a new roll to a web running past the surface of the new roll from an expiring roll after the new roll is accelerated to running web speed, in combination with means for applying a variable tension to the surfaces of said rolls, a conductive control actuator on the new roll web adjacent its leading end, means for splicing the leading end of the new roll web to a web running past the new roll from an expiring roll, electrical contacts disposed adjacent the path of the webs leaving the surface of the new roll and adapted to be electrically connected by said conductive control actuator after the splice is made, and means responsive to electrical connection of said contacts for increasing the tension applied to the surface of the new roll.

14. In apparatus for splicing the leading end of the web on a new roll to a web running past the surface of the new roll from an expiring roll after the new roll is accelerated to running web speed, in combination with means for applying a variable tension to the surfaces of said rolls, a conductive control actuator on the under surface of the new roll web adjacent its leading end, means for splicing the outer surface of the leading end of the new roll web to a web running past the new roll from an expiring roll, electrical contacts disposed in contact with the under surface of the webs leaving the surface of the new roll and adapted to be electrically connected by said conductive control actuator after the splice is made, and means responsive to electrical connection of said contacts for increasing the tension applied to the surface of the new roll.

15. In apparatus for splicing the leading end

of the web on a new roll to a web running past the surface of the new roll from an expiring roll after the new roll is accelerated to running web speed, in combination with a rotatable reel having spaced arms respectively carrying an expiring roll and a new roll, and flexible tension means adjacent said reel for contacting varying portions of the surfaces of the rolls on said reel as the reel is turned to different position, a pair of control actuators on the new roll web adjacent its leading end, means for pressing the web running from the expiring roll against the surface of the new roll to splice the leading end of the new roll web to the web running from the expiring roll, means responsive to movement of one of said control actuators on the new roll surface for actuating said web pressing means, and means responsive to the movement of the other of said control actuators away from the surface of the new roll after the splice is made for turning said reel to advance the new roll into said tension means.

16. In apparatus for splicing the leading end of the web on a new roll to a web running past the surface of the new roll from an expiring roll after the new roll is accelerated to running web speed, in combination with a rotatable reel having spaced arms respectively carrying an expiring roll and a new roll, and flexible tension means adjacent said reel for contacting varying portions of the surfaces of the rolls on said reels as the reel is turned to different positions, a pair of control actuators on the new roll web adjacent its leading end, means for pressing the web running from the expiring roll against the surface of the new roll to splice the leading end of the new roll web to the web running from the expiring roll, means for severing the web running from the expiring roll, means responsive to movement of one of said control actuators on the new roll surface for actuating said web pressing means, and means responsive to the movement of the other of said control actuators away from the surface of the new roll after the splice is made for turning said reel to advance the new roll into said tension means and actuating said severing means.

OSCAR C. ROESEN.

Certificate of Correction

Patent No. 2,413,581.

December 31, 1946.

OSCAR C. ROESEN

It is hereby certified that errors appear in the printed specification of the above numbered patent requiring correction as follows: Column 11, line 49, claim 15, for "or splicing" read *for splicing*; column 12, line 11, same claim for "or pressing" read *for pressing*; and that the said Letters Patent should be read with these corrections therein that the same may conform to the record of the case in the Patent Office.

Signed and sealed this 4th day of March, A. D. 1947.
